UNITED STATES PATENT OFFICE

EDWARD JAMES YOUNG, OF ST. LOUIS, MISSOURI.

SHOE-SHINING DEVICE.

1,250,069.

Specification of Letters Patent. Patented Dec. 11, 1917.

Application filed August 12, 1916. Serial No. 114,541.

To all whom it may concern:

Be it known that I, EDWARD J. YOUNG, a citizen of the United States, residing at St. Louis, in the county of St. Louis City, State of Missouri, have invented a new and useful Shoe-Shining Device; and I do hereby declare the following to be a full, clear, and exact description of the invention, such as will enable others skilled in the art to which it appertains to make and use the same.

The present invention relates to a shoe shining device, and has for its object to provide an article of this character which embodies novel features of construction whereby the toes and heels of shoes may be easily and thoroughly polished, and this accomplished while in a sitting position and without the necessity of stooping over to any objectionable extent.

Further objects of the invention are to provide a shoe shining device which is simple and inexpensive in its construction, which is light and compact and can be easily moved from place to place, which can be readily taken apart and packed in a small amount of space, and which enable the shoes to be thoroughly shined with a minimum amount of labor.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a side elevation of a shoe shining device constructed in accordance with the invention, portions being broken away and shown in section, and the respective positions of the polishing strip for operating upon the heel and toe portions of the shoe being indicated by dotted lines.

Fig. 2 is a top plan view of the device with the position of the polishing strip when acting upon the heel end of the shoe indicated by dotted lines.

Fig. 3 is a transverse sectional view on the line 3—3 of Fig. 2, the position of the polishing strip or cloth when acting upon the toe portion of the shoe being indicated by dotted lines.

Fig. 4 is a longitudinal sectional view 55 through the forward end of the shoe polishing device, on the line 4—4 of Fig. 2.

Corresponding and like parts are referred to in the following description and indicated in all the views of the drawing by the same 60 reference characters.

Specifically describing the present embodiment of the invention, the numeral 1 designates a foot plate which has substantially the outline of the bottom of a shoe, the rear 65 end thereof being curved and provided with an upstanding flange 2 against which the heel of the shoe 3 is placed when positioning the shoe upon the device. The heel end of the foot plate 1 is provided with laterally projecting wings or extensions 4 which are shown as arranged in the plane thereof, said wings being provided at their outer ends with lugs or enlargements, 5 having forwardly and upwardly inclined threaded 70 openings for the reception of the lower ends of the pivot bolts 6. Rollers 7 are loosely mounted upon these pivot bolts 6, and disk members 8 are interposed between the upper ends of the rollers 7 and the heads 6^a of the 75 pivot bolts 6. A long strip 9 of cloth or other suitable polishing material is used in connection with the device for polishing the shoes, and when polishing the heel end of the shoe an intermediate portion of the strip 80 9 is wrapped around the shoe heel, end portions of the strip being brought around the rollers 7 and carried upwardly. The extremities of the polishing strip 9 may be 85 grasped in the hands and the strip reciprocated back and forth so as to cause the intermediate portion thereof to rub against the heel end of the shoe and polish the same, the movements of the strip being properly 90 directed by the inclined rollers 7.

The bottom of the foot plate 1 is provided at a point spaced from the opposite ends thereof with transverse ribs 10, and also with a longitudinally extending rib 11 running along the longitudinal axis of the foot 100 plate and connecting the two transverse ribs 10, said ribs serving to strengthen and reinforce the foot plate so that it can be given a light construction. Each end of the foot plate is supported by a transversely disposed 105 standard A, said standards terminating at their lower ends in the feet 12 and being provided at their upper ends with flanges

tops 13 fitting against the bottom of the foot plate and also bearing against the sides of the respective transverse ribs 10. Suitable fastening members such as the screws 14 pass through the opposite end portions of the foot plate 1 and engage the flanged tops 13 of the respective standards A, and owing to the fact that the upper ends of the standards engage the transverse ribs 10, said standards are held securely against rotation about a vertical axis.

The standards A are similar in construction, and each of them is provided with a pair of bosses 15, the corresponding bosses of the two standards being in alignment with each other, and said bosses being located toward the outer sides of the standards. A pair of horizontal rollers 16 have the ends thereof journaled within the corresponding bosses of the two standards, said rollers being parallel to each other and arranged in a horizontal position under the foot plate 1 at opposite sides thereof. When polishing the toe end of the shoe 3, the strip 9 of the polishing cloth is carried around the horizontal rollers 16 and over the top of the shoe, the extremities of the polishing strip being grasped in the hands so that it can be suitably reciprocated. By using a long polishing strip 9 the operator can manipulate the device while in a sitting position and avoid the necessity of any excessive stooping.

The device is light and compact in construction when assembled, as shown, and can be easily moved from place to place, although when it is desired to pack the device, it can be readily taken apart and packed in a very small amount of space. By removing the screws 14 the standards A are detached from the foot plate and the horizontal rollers 16 drop out of position. The inclined pivot bolts 6 can also be unscrewed from the enlargements 5 and the inclined rollers 7 detached. It will thus be seen that the device is susceptible of being readily knocked down for shipping purposes.

Having thus described the invention,

what I claim as new and desire to secure by Letters Patent, is:-

1. A shoe shining device, including a longitudinally extending foot plate provided at points toward opposite ends thereof with downwardly projecting transverse ribs, and also provided with a longitudinal rib extending between the transverse ribs, transverse standards projecting downwardly from the ends of the foot plate and formed with flat tops which fit against the lower face of the foot plate and bear laterally against the transverse ribs, said standards being provided at points below the foot plate and on opposite sides thereof with corresponding bosses, fastening members securing the foot plate to the tops of the standards, said standards being held against rotation by engagement with the transverse ribs, and a pair of polishing cloth guide rollers having the ends thereof journaled within the bosses of the standards and arranged under the foot plate in a parallel relation to each other and to the plane of the foot plate.

2. A shoe polishing device including a longitudinally extending foot plate provided upon opposite sides of the heel end thereof with laterally projecting integral wings which terminate at their outer ends in enlargements formed with forwardly and upwardly inclined threaded openings, a pair of upwardly and forwardly inclined pivot bolts having the lower end thereof screwed into the said openings of the enlargements, polishing cloth guide rollers loose upon the inclined pivot bolts for engaging the polishing cloth when operating upon the heel of a shoe, and polishing cloth retaining disk members at the upper ends of the rollers.

In testimony whereof I have signed my name to this specification in the presence of two subscribing witnesses.

EDWARD JAMES YOUNG.
